UNITED STATES PATENT OFFICE

JACK FORDHAM PARKER, OF CODSALL, ENGLAND, ASSIGNOR TO LOW TEMPERATURE CARBONISATION LIMITED, OF LONDON, ENGLAND

CLOSURE MECHANISM FOR RETORT DOORS

Application filed June 4, 1927, Serial No. 196,590, and in Great Britain June 7, 1926.

This invention relates to doors for closing the lower ends of retorts used in the distillation of carbonaceous substances and the manufacture of coal gas and to like apparatus, and has for its object to provide a simple construction of door and supporting mechanism whereby effective closure of the retort or the like may be secured and which is adapted to be readily dismantled for the purpose of inspection or repair.

According to the invention the door is hinged in mountings such that when in the closed position the door is free of the mountings and is maintained upon the seat by pressure applied at one or more positions at the middle of the door or at a position or positions between the middle and the edges of the door.

According to the invention, moreover, the door is hinged to a member by which pressure is applied upon the door. The said member may for this purpose be pivoted and provided with lugs for the reception of the pivot pins of the door and with an arm the outer end of which engages the door to apply pressure thereon.

According to the invention, moreover, the door is advantageously mounted by hinge pins which are received into open bearings such that when the door is closed the weight of the door is taken off the bearings, while when the door is required to be removed the pivot pins may be lifted directly from the bearings.

According to the invention, moreover, the member upon which the door is hinged is carried by a spindle or pivot which is mounted in open bearings whereby it may be readily removed.

The invention further comprises the details of construction hereinafter described, and it will be understood that the invention is not limited to such features of construction.

The invention is hereinafter described with reference to the accompanying diagrammatic drawings in which

Figure 1 is a sectional elevation of the lower part of a retort fitted with a door according to the invention,

Figure 2 is a cross section corresponding to Figure 1, on the line 2—2 Figure 1.

Figure 3 is a cross section corresponding to Figure 2 but with the door and other fittings removed.

Figure 4 is a detail plan view of the pressure arm.

Figure 5 is a cross section corresponding to Figure 4 on the line 5—5, Figure 4.

Figure 6 is a detail view in elevation of the shaft upon which the pressure arm is pivoted, and

Figures 7 and 8 are views in elevation, taken at right angles, of suitable gear for the operation of the door, drawn to a smaller scale.

In carrying the invention into effect in its application to a door adapted for closure of a series of integrally formed retorts or a retort of oblong cross section and with reference to the accompanying diagrammatic drawings, the retort *a* is provided with a flange *a*¹ a short distance from the lower end, which flange is received upon a corresponding flange or seating *b*¹ formed in a supporting fitting *b* upon which the retort *a* is mounted, the relative disposition being such that the lower extremity of the retort projects below the seating or flange *b*¹ of the said fitting *b*.

The said fitting *b* is conveniently provided as a casing of rectangular or other suitable section and on one of the lateral walls thereof there are provided two or more brackets or lugs *c*, *c*¹ formed on the upper faces with semi-cylindrical recesses *c*², *c*³ to serve as bearings for the pivot pin or shaft *d* of the pressure arm *e* by which the door *f* is maintained in the closed position. The said pressure arm *e* is advantageously formed to project laterally from a sleeve *e*¹ adapted to be fitted upon the said pivot pin or shaft *d*, the said sleeve *e*¹ being formed with two or more inner bearing portions *e*² having flat surfaces or of square cross section, and adapted to fit upon similar flat surfaces or portions *d*¹ of square cross section provided upon the pivot pin or shaft *d*. The sleeve *e*¹ is advantageously also formed with integral lugs or brackets *e*³ at or near the extremities, which lugs or brackets *e*³ are formed with open slots or

recesses e^4 for the reception of pivot pins f^1 provided upon the door f .

The door f which generally follows the shape of the lower end of the retort a or the 5 retort block, is suitably provided upon the upper face with a machined bearing ridge or rib f^2 adapted to engage the lower face of the extremity of the retort a or of a flange thereon. The lower face of the door f is provided on one side with lugs f^3 in which are 10 disposed the pivot pins f^1 adapted to be loosely received into the slots e^4 in the brackets or lugs e^5 upon the sleeve e^1 before referred to. The lower face of the door f is further provided in a determined position, for example, 15 approximately at the middle with a boss or bearing surface f^4 with which the outer or free end of the pressure arm e may contact and is advantageously strengthened to resist 20 the pressure applied by the said arm e by means of ribs or webs f^5 radiating from the said boss or bearing surface f^4 towards the outer edges of the door f .

The pivot pin or spindle d upon which the 25 pressure arm is mounted is conveniently provided at one end with a sleeve d^2 integrally or otherwise secured thereto, which sleeve serves to receive the end of an operating shaft g (Figures 7 and 8), the cross section of the bore of the sleeve d^2 and of the end of the operating shaft being suitably formed to prevent relative rotation.

The shaft g extends outwardly from the fitting b and has fixedly mounted upon it at 30 the outer end a toothed sector g^1 in engagement with a worm g^2 fixed upon a transversely disposed spindle g^3 carrying a chain wheel g^4 or control wheel by which it may be rotated to effect movement of the operating 35 shaft g . The outer end of the operating shaft g and the spindle g^3 are supported in bearings provided upon a bracket g^5 for fixture in a convenient position upon the retort setting. It will be understood that other 40 suitable means for the operation of the door may be provided.

In the use of the door f it will be understood that the door being in the open position and dependent from the brackets or lugs e^3 upon the sleeve e^1 before referred to, rotation of the pivot pin or shaft d carrying the sleeve e^1 serves to revolve the pressure arm e in a direction to engage with the boss or bearing surface f^4 upon the door f and to bring the door about the pivot pins f^1 into a 50 position to close the retort a , a determined pressure being applied upon the operating shaft fixed to the sleeve d^2 to maintain the door f in the closed position.

In the closed position when the door f is applied under the pressure of the arm e , the pivot pins f^1 upon the door rise freely within the slots e^4 of the lugs or brackets and the door f is thus entirely free to contact with the retort a and thus to close it effectively.

When it becomes necessary for the door to be dismantled for examination or repair, it will be understood that the door having been moved into the open position it may be readily removed, while when it is desired to remove the pressure arm or sleeve for inspection or repair it is merely necessary to withdraw the operating shaft from engagement with the sleeve on the pivot pin or shaft when the latter can be readily lifted from the pin bearings upon the fittings before referred to and the sleeve carrying the pressure arm may then be withdrawn from the pivot pin or spindle by relative longitudinal movement or disengage the engaging flat surfaces or 80 square portions.

I claim:

1. Closure mechanism for retort doors, comprising pivotal means upon the door at a position near the edge thereof, a pivot shaft of fixed position near the said edge of the door and beside the outlet aperture of the retort, brackets mounted upon and adapted to be rotated on the said pivot shaft and with which said pivotal means are engaged, a pressure arm in fixed relation to the said brackets and adapted to be rotated therewith about the pivot shaft, said pressure arm extending beyond the said brackets and being adapted to contact with the outer face of the said door, and means for effecting rotary adjustment of the said brackets and pressure arm about the said pivot shaft for opening and closing the said door, substantially as hereinbefore described. 100

2. Closure mechanism for retort doors, comprising pivot pins for suspending the door and provided beneath and on the outside of the said door near its edge, a pivot shaft in fixed position situated beside the outlet aperture of the retort, brackets having open slots therein and adapted to be rotated on the pivot shaft, the said pivot pins being adapted to rest within the open slots in the said brackets on the said door being lowered from its closed position, a pressure arm in fixed relation to the said brackets and adapted to be rotated therewith on the said pivot shaft, the said arm extending beyond the said brackets and being adapted to contact with the outer face of the said door to press upon and retain the door in its position of closure, and means for effecting rotary adjustment of the said brackets and pressure arm about the pivot shaft for opening and closing the 110 said door, substantially as hereinbefore described. 115

3. Closure mechanism for retort doors, comprising pivot pins mounted beneath and on the outer face of the door near the edge thereof, a pivot shaft disposed beside and beneath the door aperture in fixed position, a sleeve mounted upon the said pivot shaft, brackets integrally formed with the said sleeve and provided with open slots therein 120

with which the said pivot pins respectively engage, a pressure arm also integral with the said sleeve and adapted to extend beyond the said brackets and to contact with the outer and lower face of the door and to press upon and retain the door in its position of closure, means for supporting the said shaft for rotation, means for removably holding the said sleeve upon the said spindle, and means for imparting movement to the said shaft to open or to close the said door, substantially as hereinbefore described.

4. Closure mechanism for retort doors, comprising pivot pins disposed beneath and on the outer face of the door near the edge thereof, a pivot shaft supported in a position beside and beneath the outlet aperture of the retort, brackets mounted upon and adapted to be rotated upon the pivot shaft, the said brackets having open slots therein of such form as to provide hook-shaped recesses for the suspension of the door by the pivot pins when the door is lowered from its closed position, a pressure arm in fixed relation to the said brackets and adapted to be rotated therewith on the said pivot shaft, the said pressure arm extending beyond the said brackets and being adapted to contact with the outer face of the said door and to press upon and retain the door in its position of closure, and means for effecting rotary adjustment of the said brackets and pressure arm about the said pivot shaft for opening and closing the said door, substantially as hereinbefore described.
